DESIGN FOR A PROTECTOR FOR A RADIATOR AIR VALVE

Max Lieberman, Brooklyn, N. Y.

Application July 12, 1937, Serial No. 70,378

Term of patent 14 years

To all whom it may concern:

Be it known that I, Max Lieberman, a citizen of the United States, residing in Brooklyn, county of Kings, and State of New York, have invented a new, original, and ornamental Design for a Protector for a Radiator Air Valve, of which the following is a specification, reference being had to the accompanying drawing, forming part thereof.

Figure 1 is a perspective view of a protector

for a radiator air valve showing my new design.

Figure 2 is a side elevation of the same, and

Figure 3 is a cross-sectional view, the section being taken as on line 3—3 in Figure 2.

I claim:

The ornamental design for a protector for a radiator air valve, substantially as shown.

MAX LIEBERMAN.
